ELECTRIC SWITCH

Frank D. Bryant, Stratford, and William R. Young, Fairfield, Conn., assignors to General Electric Company, a corporation of New York

Application February 15, 1939, Serial No. 256,516

13 Claims. (Cl. 200—8)

The present invention relates to electric switches, and more particularly to a rotary switch adapted to control a plurality of circuits. Switches of this type have a wide application. 5 They are well adapted for use in connection with speed control circuits for electric motors.

It is an object of this invention to provide a simple and rugged switch construction which is easily operated and which insures a circuit connection of low electrical resistance. 10

It is another object of this invention to provide an electric switch having relatively few parts which are easily assembled and which may be manufactured at low cost.

15 Further objects and advantages of the present invention will become apparent as the following description proceeds, reference being had to the accompanying drawing in which Fig. 1 is a plan view partly broken away, of a switch embodying our invention; Fig. 2 is a sectional view taken along the line 2—2 of Fig. 1; Fig. 3 is a sectional view along the line 3—3 of Fig. 1, and Fig. 20 4 is an exploded view of the switch shown in Fig. 1 showing the details of construction of the various parts of the switch.

As illustrated in the drawing a support or housing for the switch mechanism is provided by the body 10 and the thumb cap or cup-shaped operating member 11, both of which are formed of 30 an insulating material such as a molded phenolic condensation product. The body is of generally cylindrical form and includes a flange 12 and an upstanding boss 13. A recess 14 opening on the lower face of the flange is defined by a wall 15 35 of generally annular shape which serves as a support for a plurality of conducting members 16. The conducting members 16 which form the stationary contact and terminal structure of the switch are preferably sheet metal stampings of 40 substantially U-shape. One arm of each U-shaped member forms a contact 17 having a V-shaped cross-section to provide two opposing contact surfaces, while the other arm of the U forms a terminal or supporting arm 18. The circuit 45 wires 19 are secured to the terminals in any suitable manner as by soldering. The annular wall 15 is provided on its outer and inner surfaces with a plurality of circumferentially spaced axially extending grooves 20 and 21 which are 50 adapted to receive the contacts and terminals respectively. The grooves 20 are of the same size and contour as the contacts 17 so that the outer surfaces of the contacts are flush with the outer surface of the switch body. The grooves 20 and 55 21 are positioned in radial alignment and are

connected on the face of the flange 12 by radially extending recesses 22 which are adapted to receive the bases of the U-shaped conducting members. The grooves 20 on the outer surface of the wall 15 extend through the flange 12 and permit the U-shaped conducting members to be assembled on the base by simply slipping them over the annular wall with each arm of the U accommodated in one of the radially aligned grooves. Axially extending barriers or ribs 23 formed on 10 the inner surface of the wall 15 between the grooves 21 serve to separate the conductors attached to the different terminals and diminish the possibility of a short circuit being established. 15

The conducting members 16 are held assembled on the annular wall 15 by an insulating washer 24 and an overlying metal plate 24a secured against the face of the flange 12 by screws 25 which engage the walls of suitable threaded openings 26 formed in the flange. Centrally located 20 apertures 27 are formed in the washer 24 and plate 24a for the reception of the circuit wires 19. A threaded nipple 28 having an end received in the aperture 27 of the plate 24a and secured thereto in any suitable manner provides a convenient means for mounting the switch. The nipple also provides a conduit for the circuit wires as they enter the switch body. Depending legs 29 formed on the plate 24a are adapted to engage notches 30 formed at diametrically opposite points on the outer edge of the washer 24 and the flange 12 to position the parts relative to each other. 25

For operating the switch the thumb cap 11 is 30 rotatably mounted on the switch body 10 by a 35 boss or hub 31 which is journaled in a bore 32 opening on the face of the boss portion 13 of the insulating body. The bore 32 opens at its other end on the floor of the recess 14 which is of 40 larger diameter than the bore so that a shoulder 33 facing the flange 12 is provided. An insulating washer 34, secured to the hub 31 of the thumb cap by a suitable screw 35, engages the shoulder 32 to hold the thumb cap and switch body in 45 operative relationship. An annular wall 36 depending from the face of the thumb cap surrounds the boss 13 of the switch body in spaced relation thereto. At one side the wall is provided with a thickened portion 37 which is provided with a substantially U-shaped slot 38 for the reception 50 of an offset portion 39 of similar shape formed on a movable bridging member of conducting material illustrated generally by the numeral 40. From another viewpoint the arrangement just described for mounting the conducting member

40 may be considered as comprising a post 41 formed integrally with the thumb cap and extending in spaced relation to the wall 36.

The movable bridging member is of substantially U-shape having a pair of opposed resilient arms 42 each of which is provided near its outer end with a spherical contact surface 43 which is struck up from the body of the bridging member. Spherical or ball contacts 44 are arranged in the bearing surfaces and are adapted to be pressed against the outer surface of the boss 13 of the insulating body by the resilient arms 42. When the thumb cap is rotated it carries with it the bridging member 40 and its associated contacts 44 which are moved from one set of contacts 17 to another to electrically connect the contacts located at diametrically opposite points on the switch body. Axially extending ribs 45 formed between the contacts 17 on the outer surface of the boss 13 cooperate with the spherical contacts 44 and the resilient arms 42 of the bridging member 40 to move the spherical contacts from one circuit-controlling position to another with a snap action when the thumb cap 11 is rotated. The opposed sides of the ribs 45 are substantially plane surfaces and lie in the same plane as the adjacent legs of the V-shaped contact members 17. In other words, the outer surface of the switch body is a succession of hill and valley portions with the trough of each valley formed by one of the V-shaped contact members 17 and the crest of each hill formed by one of the axially extending ribs 45. With this construction the spherical contacts follow the contour of the outside surface of the switch body under the action of the resilient arms 42. It is apparent that the spherical contacts always tend to return to the troughs formed by the contacts 17 and, in this way, position the fixed and movable parts of the switch relative to each other. Since the spherical contacts are free to rotate relative to the bearing surfaces formed in the resilient arm, the force required to rotate the thumb cap is reduced to a minimum.

45 In order to provide an "off" position, no contacts are provided on the opposed surfaces 46 of the boss 13. These surfaces have the same V-shape as those formed by the stationary contacts 17 and the ribs 45. It is apparent that the switch 50 may be rotated in either direction from one circuit-controlling position to another. In order to indicate the position of the spherical contacts relative to the switch body the thumb cap 11 is provided with an indicating arrow 47.

55 While we have shown and described a switch construction in which six stationary contact elements are arranged to provide three "on-circuit" positions of the switch, it is to be understood that any number of contacts may be arranged on the switch body at diametrically opposite points, and that any desired number of "off" positions may be provided by simply omitting pairs of contacts and grooves and leaving in place thereof opposed faces of the boss 13 of insulating material.

60 The switch described above is very easily assembled. After the circuit wires 19 have been secured to the terminals of the U-shaped conducting members 16, the latter are assembled on the switch body by simply slipping them over the 65 annular wall 15 with the legs of each U-shaped member received in one pair of the radially aligned grooves 20 and 21 formed on the outer and inner surfaces of the annular wall. The insulating washer and metal plate 24 and 24a are then secured 70 against the face of the flange by screws 25

and hold the conducting members assembled on the switch body. The movable conducting member 40 is then placed in the thumb cap 11 with the offset portion 39 positioned in the slot 38. The ball contact members are placed in the spherical contact surfaces 43 formed in the opposed arms of the conducting member 40 and the thumb cap assembled on the switch body by inserting the boss 31 in the bore 32. The assembly is completed by inserting the washer 34 and screw 35 in the recess 14 and threading the screw into the boss 31 of the thumb cap. When the switch is assembled the flange 12 of the switch body serves to hold the conducting member 40 assembled in the thumb cap. 15

From the foregoing it is clear that a very compact and rugged switch construction is provided by the present invention in which movable contacts may be moved with a snap action in either direction from one circuit-controlling position to another by simply rotating the thumb cap which carries with it the movable contact structure. The resilient arms of the movable contact structure cooperate with the ball contacts and the stationary contact members to insure good electrical connections and at the same time the rolling action of the ball contacts provides a switch which is very easily operated. 20 25

What we claim as new and desire to secure by Letters Patent of the United States is: 30

1. In a switch, a body of insulated material having a substantially annular shaped wall, said wall having a plurality of spaced axially extending grooves on the inner and outer surfaces thereof, a plurality of stationary conducting members 35 of U-shape each having a contact portion positioned in a groove on the outer surface of said wall and a terminal portion positioned in a groove on the inner surface of said wall, an operator of insulating material rotatably mounted on said body, a pair of spherical contact members, a bridging member of conducting material carried by said operator and having oppositely disposed arms adapted to receive said spherical contact members and hold them against the outer surface 40 of said annular wall to connect electrically certain of the conducting members located in said grooves. 45

2. In a switch, a body of insulating material including a raised central portion, a plurality of 50 conducting members mounted in spaced relation on the outer surface of said central portion, a cap of insulating material rotatably mounted on said body, a substantially U-shaped bridging member of conducting material mounted in said cap and having a driving connection therewith, said bridging member having oppositely disposed arms straddling said central portion, and contacts associated with the arms of said bridging member for engaging certain of said conducting members. 55 60

3. In a switch, a body of insulating material having a substantially annular shaped wall, a plurality of stationary conducting members of U-shape arranged in spaced relation on said wall, each of said conducting members having a contact portion positioned on the outer face of said wall and a supporting portion positioned on the inner face of said wall, a cap of insulating material rotatably mounted on said base, a substantially U-shaped bridging member of conducting 70 material mounted in said cap and having oppositely disposed arms spanning said annular wall, and contacts associated with the arms of said bridging member for engaging certain of the contact portions of said conducting members. 75

4. In a switch, a body of insulating material having a substantially annular shaped wall, said wall having a plurality of spaced axially extending grooves on the inner and outer faces thereof, a plurality of conducting members of U-shape each having a contact portion positioned in a groove on the outer face of said annular wall and a terminal portion positioned in a groove on the inner face of said wall, a cap of insulating material rotatably mounted on said body, said cap having a depending wall surrounding said annular shaped wall, said depending wall having an axially extending slot formed therein, a bridging member of conducting material having an offset portion positioned in said slot for moving said bridging member with said cap, said bridging member including oppositely disposed arms having bearing surfaces formed therein, and spherical contacts positioned in said bearing surfaces adapted to engage the contact portions of certain of said conducting members.
5. In a switch, a body of insulating material having an upstanding boss, an axially extending recess in said boss, a plurality of pairs of axially extending grooves spaced around the outer surface of said boss in diametrically opposed relation, conducting members positioned in said grooves, a cap having a centrally located hub positioned in said recess to mount said cap on said base and permit rotation relative thereto, said cap having a depending wall surrounding said boss, an axially extending slot in said wall, a bridging member of conducting material having an offset portion positioned in said slot for moving said bridging member with said cap, said bridging member including oppositely disposed arms having contact surfaces associated therewith arranged to electrically connect the conducting members located in any one of said pairs of diametrically opposed grooves.
6. In an electric switch, a body of insulating material having a flanged portion and an upstanding boss, a plurality of conducting members secured in spaced relation around the outer surface of said boss, a thumb cap rotatably mounted on said body, a substantially U-shaped bridging member of conducting material slidably mounted in said cap and having a driving connection therewith, the opposed arms of said U-shaped member having contacts carried thereby adapted to engage certain of said conducting members, said flanged portion being constructed and arranged to engage the lower edge of said bridging member to hold it assembled in said thumb cap.
7. In a switch, a body of insulating material having a flanged portion and an upstanding boss, a recess opening on the face of said flange and a recess of smaller diameter opening on the face of said boss, a shoulder formed on said body at the junction of said recesses, a plurality of axially extending grooves on the outer face of said boss, conducting members positioned in said grooves, a cup-shaped cap member having a centrally disposed hub adapted to extend into said smaller recess and position said cap on said body and permit rotation relative thereto, an axially extending post on said cap, a bridging member of conducting material having an offset portion adapted to engage said post to form a driving connection between said cap and said bridging member, said bridging member having oppositely disposed arms spanning said boss, said arms having spherical bearing surfaces formed in the ends thereof, spherical contact members positioned in said bearing surfaces and pressed against the outer surfaces of said boss portion by the resilient arms of said bridging member, and means secured to said hub for engaging said shoulder to hold said cap on said base.
8. In an electric switch for controlling a plurality of circuits, a body of insulating material having a flanged portion and an upstanding boss, said body having an axially extending bore formed therein, a plurality of axially extending grooves on the inner and outer surfaces of said body, a plurality of U-shaped conducting members having their opposite arms received in said grooves, a cup-shaped operating member having a centrally disposed hub extending into said bore to position said operating member on said body and permitting rotation relative thereto, an axially extending post formed on said cap, a bridging member of conducting material having an offset portion engaging said post to form a driving connection between said operating member and said bridging member, said bridging member having oppositely disposed resilient arms spanning said boss, and contact surfaces associated with said arms and pressed against the outer surface of said boss by the resilient arms of said bridging member whereby rotation of said cap moves said bridging member and its associated contacts from one circuit-controlling position to another.
9. In a switch for controlling a plurality of circuits, a body of insulating material having a flanged portion and an upstanding boss, conducting members secured in spaced relation around the outer surface of said boss, an axially extending recess opening on the face of said boss, a cup-shaped cap member having a centrally disposed hub extending into said recess to position said cap on said body and permit rotation relative thereto, a U-shaped slot in the wall of said cap, a bridging member of conducting material having an offset portion positioned in said slot to form a driving connection between said cap and said bridging member, the flanged portion of said base being constructed and arranged to engage the lower edge of said bridging member to hold it in said cap, said bridging member having resilient oppositely disposed arms spanning said boss, said arms having spherical bearing surfaces formed near the ends thereof, spherical contact members positioned in said bearing surfaces and pressed against the outer surface of said boss by the resilient arms of said bridging member, whereby rotation of said cap moves said bridging member from one circuit-controlling position to another.
10. In a switch for controlling a plurality of circuits, a body of insulating material, a plurality of contacts arranged in spaced relation around the outer surface of said body, axially extending ribs formed on said body between adjacent contacts, an operating member of insulating material rotatably mounted on said body, a bridging member of conducting material secured to said operating member and adapted to rotate therewith, said bridging member having resilient oppositely disposed arms spanning said body, said arms having spherical bearing surfaces formed near the ends thereof, spherical contact members positioned in said bearing surfaces and pressed against the outer surface of said body by the resilient arms of said bridging member, said axially extending ribs cooperating with said resilient arms and said spherical contact members to move said contact members from one circuit-controlling position to another with a snap action when said operating member is rotated.

11. In a switch, a body of insulating material having a substantially annular-shaped wall, said wall having a plurality of spaced axially extending grooves on the inner and outer surfaces thereof, a plurality of stationary conducting members of U-shape each having a contact portion positioned in a groove on the outer surface of said wall and a terminal portion positioned in a groove on the inner surface of said wall, an operator of insulating material rotatably mounted on said body, and means of conducting material carried by said operator and movable therewith to connect electrically certain of the conducting members located in said grooves, said means including a pair of spherical contact members and a pair of oppositely disposed arms adapted to receive said contact members and hold them against the outer surface of said annular wall and the conducting members positioned thereon.
12. In a switch, a body of insulating material having a substantially annular-shaped wall, a plurality of stationary conducting members of U-shape arranged in spaced relation on said wall, each of said conducting members having a contact portion positioned on the outer face of said wall and a supporting portion positioned on the inner face of said wall, and means secured to said body and engaging said conducting members to prevent their removal from said wall, an operating member of insulating material rotatably mounted on said base, and means of conducting material mounted in said operator, said means including a pair of oppositely disposed arms spanning said annular wall and contacts associated therewith for engaging the contact portions of certain of said conducting members.
13. In a switch for controlling a plurality of circuits, a body of insulating material, a plurality of contacts arranged in spaced relation around the outer surface of said body, axially extending ribs formed on said body between adjacent contacts, an operating member of insulating material rotatably mounted on said body, means formed of conducting material secured to said operating member for rotation therewith, said means including oppositely disposed resilient arms spanning said body, said arms including spherical bearing surfaces formed near the ends thereof, spherical contact members positioned in said bearing surfaces and pressed against the outer surface of said body by said resilient arms, said axially extending ribs cooperating with said resilient arms and said spherical contact members to move said contact members from one circuit-controlling position to another with a snap action when said operating member is rotated.
